(57) **CLAIM**

The ornamental design for a cooling unit cover as shown and described.

DESCRIPTION

FIG. 1 is a front left perspective view of a cooling unit cover; FIG. 2 is a cross-sectional view of a front side thereof; FIG. 3 is a front side view thereof, the rear side view being a mirror image;

FIG. 4 is a top view thereof, and in which the locations of the sectional views of FIGS. 2 and 7 are indicated;

FIG. 5 is a bottom view thereof;

FIG. 6 is a left side view thereof, the right side view being a mirror image; and,

FIG. 7 is a cross-sectional view from the left side view thereof.

Broken lines illustrate portions of the cooling unit cover, that form no part of the claimed design.
